VARIABLE RESISTOR DEVICE

David G. C. Luck, Princeton, N. J., assignor to
 Radio Corporation of America, a corporation
 of Delaware

Application March 31, 1945, Serial No. 585,954

7 Claims. (Cl. 201—55)

1

This invention relates to variable resistor devices, and more particularly to electrical devices of the variable resistor type for the generation of specified mathematical or empirical functional relations, such as are used in certain electrical computer systems.

The principal object of the instant invention is to provide an improved variable resistor structure which may be designed readily to provide a predetermined resistance vs. angular rotation characteristic.

Another object is to provide a device of the described type in which the desired resistance-rotation characteristic may be attained to a great degree of accuracy and accurately maintained under conditions of continuous operation.

A further object of the present invention is to provide devices of the described type which will easily provide resistance-rotation characteristics which are difficult or impossible to achieve with conventional prior art structures.

These and other objects will become apparent to those skilled in the art upon consideration of the following description, with reference to the accompanying drawing, of which

Figure 1 is a front elevation of one embodiment of the invention,

Figure 2 is a side elevation of the device shown in Figure 1,

Figure 3 is a front elevation of a modification of the device shown in Figure 1,

Figure 4 is a side elevation of the structure of Figure 3,

Figure 5 is an illustration of one type of resistor element which may be used in the structures of Figures 1 and 3,

Figure 6 is a schematic diagram of a modification of the structures of Figures 1 and 3, and

Figure 7 is a front elevation of a modification of the structure of Figure 3.

Variable resistors are used quite generally for the purpose of controlling voltage or current in accordance with a predetermined function of the angular position of a shaft. The usual volume control of a conventional radio receiver is one example of such use. The accuracy of the relationship between shaft position and output-to-input voltage ratio is a secondary matter in the ordinary radio receiver.

Certain other applications of variable resistors require that the resistance-rotation characteristic be maintained very closely to secure successful operation of the system. For example, some types of electrical computer systems employ variable resistors in such manner that the precision

2

of the computer is directly related to that of the resistor. Furthermore, the relationship between resistance and rotation may not be a continuously increasing or decreasing function, as in the radio volume control, but may increase through one portion of the angular range of shaft rotation and decrease through another portion. The required function may be such that the resistance should change very gradually, or not at all, throughout some substantial angle of shaft rotation. Requirements of this nature are difficult to meet with variable resistors of prior art types, usually necessitating mechanical complexities such as cam drives between the control shaft and the variable resistor.

According to the present invention, a substantially linear resistance element is used in cooperation with a line contact device instead of the usual contact device in which the same contact point or surface touches the resistor at all shaft positions. It is proposed to move the resistor element and the contact element relatively to each other in such manner that a different portion of the contact line touches the resistor at each different position of the control shaft. It is then a relatively simple matter to design the device to provide substantially any desired resistance-rotation characteristic, by making the contact line follow a correspondingly predetermined curve.

Refer to Figures 1 and 2. A shaft 1 is mounted for rotation in a bearing 3 secured in a supporting plate 5. A contact plate 7 is supported parallel to the plate 5 by spacer members 9 secured to the plates 5 and 7. A hole 11 is provided in the plate 7. The shaft 1 extends through the hole 11, and supports near its outer end an arm 13. The arm 13 extends substantially radially of the shaft 1 and is secured thereto by a conventional collar and set-screw arrangement. The arm 13 is provided with an offset extension 15 having a pair of lugs 17 standing at right angles thereto, approximately parallel to the shaft 1.

A rod 19 is supported pivotally upon the lugs 17 by means of screws 21. A pair of bracket members 23 are secured to respective ends of the rod 19, and support between their outer ends a pair of strips 25. A strip-like resistor element 27, shown more clearly in Figure 5, is clamped between the strips 25. The resistor element comprises a strip of insulating material 29, wound throughout the major portion of its length with resistance wire 31. It will be apparent without further illustration that the resistor 27 may com-

prise a solid body of resistive material, rather than a wire wound element.

The proportions of the structure are such that the edge of the resistor 27 which faces the contact plate 7 runs substantially radially of the shaft 1. A leaf spring 33 is secured to one of the strips 25 and bears against the member 18 to urge the resistor assembly toward the contact plate 7.

The ends of the resistor 27 are connected to wires 35 and 37, which extend through the hole 11 to a pair of slip rings 39 and 41, respectively. The rings 39 and 41 are mounted on a body 43 of insulating material secured to the shaft 1. A pair of brushes 45 and 49 are mounted on a block 51 of insulating material, in contact with the rings 39 and 41, respectively.

The plate 7 is provided with a contact rib 53 which stands up from the plate 7 in the direction of the resistor element 27. The rib 53 is laid out in a curve corresponding in shape to the polar graph of the desired resistance-rotation characteristic. In the present illustration this curve is a limacon, corresponding to the equation

$$r=a+b \sin \theta$$

The plate 7 may comprise a solid body of conductive material, or may be a body of insulating material provided with a conductive surface. In the latter instance, only the rib 53 need be conductive. However, it is preferred to use a thin sheet of conductive material, with the rib 53 embossed or otherwise formed thereon, secured to a relatively thick plate of insulating material. The rib 53 is connected to a terminal 55.

In the operation of the described device, the resistor 27 touches the rib 53 at one point. The position of the point longitudinally of the resistor 27 depends upon the angular position of the shaft 1. The resistance which appears between the terminal 55 and the contact brush 45 is proportional to the distance of the point of contact from the inner end of the resistor 27. Thus as the shaft 1 is rotated, the resistance between the terminal 55 and the contact 45 will vary in proportion to $a+b \sin \theta$, where θ is the angular position of the shaft 1 with respect to a reference line. (The line A—A in Figure 1.) If a voltage E is applied between the contacts 45 and 49, the voltage between the terminal 55 and the contact 45 will be

$$E'=E(a+b \sin \theta)$$

With the structure shown in Figures 1 and 2, the shaft 1 may be rotated continuously in one direction to provide cyclical repetition of the function. The described curve is particularly useful in providing a sine or cosine function, since the constant term a may be cancelled by providing an additional fixed voltage $E''=aE$ in series with the connection to the contact 45 or the terminal 55, in proper polarity to oppose the constant component aE of the voltage E' . The same thing may be accomplished by establishing the point at radius a on element 27 at reference potential, as by providing a grounded tap fixed on the element at that radius and taking the output voltage between the rib 53 and ground. The cosine function is readily provided by moving the reference line 90°. This may be done by altering the angular position of the arm 18 on the shaft 1, rotating the contact plate 7 through 90°, or by changing the connection of the shaft 1 to its driving means.

In the event that a continuously repeating function is not required, the structure shown in

Figures 3 and 4 may be preferred. In this case a contact rib 53 is embossed or otherwise formed on the surface of a thin metal sheet 57. The sheet 57 is provided with extensions 59 which are secured to a block 61 of insulation. The top and bottom edges of the main portion of the sheet 57 are bent back to form stiffening flanges 60. The block 61 carries a shaft supporting member 63, through which a shaft 65 extends. A radial arm 67 is secured to the shaft 65, and supports a radially extending resistor element 69 parallel to the sheet 57 and in contact with the rib 53.

The operation of the structure of Figure 3 is substantially identical with that of the device of Figure 1, with the exception that the angular range of operation is limited to about 90°. The extensions 59 on the member 57 serve as leaf springs, maintaining contact between the rib 53 and the edge of the resistor element 69. It should be noted that this structure, like that of Figure 1, can be made to increase and decrease resistance during rotation of the control shaft in one direction, and will operate without difficulty with functions requiring a portion of low or zero change of resistance with rotation.

In some cases it may be necessary to vary resistance in accordance with a function which changes very rapidly with rotation through a portion of the operating range. Figure 6 shows schematically a typical curve 70 which might be required. The rate of change of radius (or resistance) with respect to θ is very low at the angle θ_1 , but increases with increase in θ through the values θ_2 , θ_3 , etc., becoming a maximum at θ_5 .

If a rectilinear resistor element, extending radially from the origin, were used, as shown in Figures 1 and 4, the angle ϕ between the resistor element and the contact line would be relatively acute at the position θ_5 . This is disadvantageous because the areas of the resistor and the rib which are in contact with each other are much larger when the angle ϕ is relatively acute.

The contact angle ϕ may be maintained at substantially 90° for all values of the angle θ by curving the resistor strip as indicated by the line 71. The curvature of the line 71 is a function of that of the curve 70, and may be made so that the crossing angle is exactly 90° at all times. It should be noted that the curve 70 is no longer a true polar graph of the required function but must be distorted in accordance with the departure of the curve 71 from a radial line.

It is preferable in practice to use a rectilinear resistance element rather than a curved one even under the conditions illustrated in Figure 7. A crossing angle sufficiently close to 90° for practical purposes may be obtained by using the rectilinear approximation of the curve 71. This is indicated by the dash line 73, which intersects the curve 71 at two points 75 and 77, and deviates from the curve 71 by the same amount at the center and at the extremes of the operating range. It is apparent that the maximum deviation of the crossing angle from 90° is relatively small.

Figure 7 shows a structure similar to that of Figure 4, but with the resistor element offset as described in connection with Figure 6 to provide minimum variation of contact angle. The reference numerals used in Figure 6 are the same as those used for corresponding elements in Figure 4.

The invention has been described as an improvement in variable resistor devices, wherein a substantially linear resistor element is used

in cooperation with a line contact device rather than the usual single point contact. The resistor and contact element are movable relatively to each other so that a different portion of the contact line touches the resistor at each different position of the control shaft. The contact line is made in a curve having a shape predetermined in accordance with the required resistance-rotation characteristic.

I claim as my invention:

1. An electrical device comprising a substantially rectilinear resistor element, a contact member having the shape of a polar graph of a predetermined voltage ratio vs. rotation characteristic to be provided by said device, means supporting said resistor element in radial relation to said contact member, and means for rotating said resistor in contact with said contact member.

2. An electrical device comprising a resistor element including a substantially rectilinear contact portion, a contact body having a raised rib of conductive material thereon, said rib lying along a line which is the shape of a polar graph of a predetermined resistance vs. rotation characteristic to be provided by said device, means supporting said resistor element with said contact portion radially of the line of said rib and in contact with said rib, and means for rotating said resistor element about the point corresponding to the origin of said graph, whereby the resistance between one end of said resistor element and said contact body varies as said predetermined characteristic.

3. An electrical device comprising a linear resistor element, a contact member having a curved shape predetermined in accordance with a voltage ratio vs. rotation characteristic to be provided by said device, means supporting said resistor element in contact with said contact member, and means for rotating said resistor about an axis substantially perpendicular to the plane of the curve of said contact member.

4. An electrical device comprising a contact body having a raised rib of conductive material thereon, said rib lying along a curve which is the shape of a polar graph of a predetermined resistance vs. rotation characteristic to be provided by said device, a shaft perpendicular to the plane of said line, with its axis through the origin of said polar graph, a resistor element including a substantially linear contact portion, and means supporting said resistor element with

its contact portion extending radially of said shaft and in contact with said rib.

5. An electrical device including a contact member having the configuration of a polar graph of an electrical function to be generated, a shaft perpendicular to the plane of said member, with its axis extending through the origin of said polar graph, a resistor element having a substantially linear contact surface, an arm secured to said shaft and extending at a right angle thereto, means supporting said resistor element on said arm with its said contact surface extending radially of said arm, and spring means urging said resistor element in a direction substantially parallel to the axis of said shaft toward said contact member.

20 6. An electrical device including a contact member having the configuration of a polar graph of an electrical function to be generated, a shaft perpendicular to the plane of said member, with its axis extending through the origin of said polar graph, a resistor element having a substantially linear contact surface, an arm secured to said shaft and extending at a right angle thereto, and means supporting said resistor element on said arm with its said contact surface extending radially of said arm.

25 7. An electrical device including a contact member having the configuration of a polar graph of an electrical function to be generated, a shaft perpendicular to the plane of said member, with its axis extending through the origin of said polar graph, a resistor element having a substantially linear contact surface, an arm secured to said shaft and extending at a right angle thereto, means supporting said resistor element on said arm with its said contact surface extending radially of said arm, and spring means urging said contact member toward said resistor element in a direction substantially parallel to the axis of said shaft.
